DOOR LOCK

Thomas W. Anderson, Susanville, Calif.

Application January 15, 1940, Serial No. 314,006

6 Claims. (CL. 70—147)

This invention relates to door locks, and its general object is to provide a lock that includes a pair of knobs having pivotally mounted shanks associated with a spring pressed locking or latching bolt for moving the same to released position upon rocking either knob.

An important object is to provide a door lock that includes pivotally mounted knob shanks for the purpose set forth, and the pivot of the shank of one knob is rotatably mounted about a ninety degree angle, while the pivot of the shank of the other knob is fixed, but of course allows rocking movement thereof, and the shanks are constructed and associated with each other in a manner so that when the first knob is turned to one of its positions, either knob can be rocked for moving the latching bolt to released position, but when turned to its other position, both knobs are held against rocking movement, with the bolt in latched position.

Another object is to provide a door lock including the features mentioned, and also key actuated means mounted in the knob of the shank having the fixed pivot for turning the shank of the other knob, by the use of a key, thus it will be seen from the foregoing, that the door can be locked and unlocked from one side by the use of a key only and from the other side, without the key, or in other words, merely by turning the knob.

A further object is to provide a door lock that includes a bolt having a pivoted cam head to facilitate the application and removal thereof with respect to its keeper or strike plate and the knobs are shaped to provide convenient gripping means to facilitate rocking the same for moving the bolt to its respective positions.

A still further object is to provide a door lock, that is simple in construction, inexpensive to manufacture, can be installed in the same manner as the conventional double knob lock, and is extremely efficient in operation, use and service.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a top plan view illustrating my lock installed in a door, with parts thereof in full

and dotted lines and the jamb, frame and strike plate in cross section.

Figure 2 is a view looking toward the free edge of the door and illustrates the knobs in normal position and arrows indicating the direction of movement thereof when rocked on the pivots of their shanks.

Figure 3 is a sectional view taken approximately on line 3—3 of Figure 2, looking in the direction of the arrows.

Figure 4 is a sectional view taken approximately on line 4—4 of Figure 2, looking in the direction of the arrows, with the bolt in normal or latched position.

Figure 5 is a sectional view somewhat like Figure 4, with the bolt in unlatched position.

Figure 6 is a perspective view of the bolt with the head thereof removed, and its actuating member applied thereto for moving the same against the action of its spring.

Figure 7 is a vertical sectional view illustrating parts in elevation and the knobs together with the associated elements thereof in normal position in full lines and in rocked position in dotted lines together with the key actuated means for locking and unlocking the door from the outer side thereof.

Figure 8 is a sectional view taken approximately on line 8—8 of Figure 7, looking in the direction of the arrows.

Figure 9 is a sectional view taken approximately on line 9—9 of Figure 7, looking in the direction of the arrows.

Figure 10 is a vertical sectional view somewhat similar to Figure 7, with the parts turned to locked position.

Referring to the drawings in detail, it will be noted that I have illustrated a lock for an outside door A of a house or the like, in that the key actuated means is included therein, as such may be eliminated when the lock is constructed for an inside door. In any event the door is provided with a frame B and a jamb C, with a strike plate 1 of the usual construction, fixed to the frame as clearly shown in Figure 1.

The lock in the form shown includes the usual narrow casing 2 that may be provided with a detachable side wall, but in any event is shown as being mounted in a mortise within the door and having an open front, closed by a plate 3 fixed to extensions 4 formed on the casing, by screws 5 that likewise secure the casing within the mortise, as best shown in Figure 4.

The plate 3 is provided with a single opening and is distinguished in that respect from the

closure plates of the usual lock or latch casings. Slidably mounted in the casing is a locking or latching bolt member that includes a relatively thin forward horizontally disposed portion 6 movable through the opening of the closure plate and has pivotally connected to the outer end thereof a cam head 7 that is likewise pivoted to ears 8 struck from the closure plate and extending inwardly therefrom. Formed on the portion 6 are rearwardly directed diverging arms 9 that have formed on the rear ends thereof flat parallel portions 10 slidably mounted on the upper and lower walls of the casing, and the rear ends of the portions 10 are inturned at right angles 15 thereto to provide flanges 11.

Formed on the bolt member at the juncture of the arms 9 with the forward portion 6 is a laterally directed abutment lug 12 for one end convolution of a coil spring 13 that has its opposite end convolution engaged with a bracket 14 fixed to the side wall of the casing, so that the spring normally holds the bolt member with its head in latching position within the keeper opening of the strike plate, as clearly shown in Figure 1.

The actuating member for moving the bolt member against the action of the spring includes a forward wall 15 having the flanges 11 engaged with the rear face thereof, and formed on the side edges of the forward wall 15 are rearwardly directed substantially semi-circular walls 16 having rectangular openings 17 therein that are disposed in registration with each other, and with openings in the side walls of the casing, 35 as well as in the door, as best shown in Figure 7. The actuating member is pivotally connected to the side walls of the casing for swinging movement, so that it can exert pressure on either of the flanges 11 when swung on its pivot, for drawing the bolt member against the action of the spring 13, or in other words to released position, as clearly shown in Figure 5.

Fixed to the opposite sides of the door by screws 17, are escutcheon plates 18 and 19 that are likewise fixed to each other by a screw bolt 20 threaded within a boss 21 formed on the inner face of the plate 18 that is secured to the outer side of the door, and the screw bolt has a kerfed head countersunk in the other plate 19. By that construction, it will be obvious that the plate 18 cannot be removed to gain access to the lock from the outside. The escutcheon plates have openings therein registering with the openings in the door and side walls of the casing, and 55 extending outwardly from the escutcheon plate 18 for disposal upon diametrically opposite sides of the opening thereof, are ears 22. The opening of the plate 19 is provided with an outwardly directed marginal flange 23, as well as has a washer like member 24 secured thereto about the opening to cooperate with the flange 23 to provide an annular guide having slidably mounted therein, a flat ring 25, with parallel ears 26 extending outwardly therefrom.

Extending through the ring 25 for disposal within the casing, as well as in the rectangular opening of one of the walls 16 of the bolt actuating member for moving the latter on its pivot, is a one piece shank 27 for a knob 28, the shank 70 being pivoted between the ears 26 and has a narrow recess 29 in its inner end. By that construction, it will be seen that the shank 27 is not only pivotally mounted for rocking movement, but is rotatably mounted. Extending 75 through the opening in the plate 18 is the shank

30 for the other knob 31 and the shank 30 is pivoted between the ears 22 by a pivot pin 32, for rocking movement. The knobs are preferably of substantially cylindrical formation in the form as shown in order to provide convenient gripping means to facilitate rocking the same, as will be apparent upon inspection of Figure 1, which illustrates the parts in normal position, consequently the knob 28 is disposed in a horizontal plane and the knob 31 is permanently 10 disposed accordingly.

The shank 30 includes an outer sleeve that terminates short of the outer wall of the casing, but has a spindle 33 mounted for rotation in the sleeve and extending through the inner end 15 thereof, with a head 34 formed on the inner end of the spindle and which extends through the opening of the adjacent walls of the casing and bolt actuating member, as clearly shown in Figure 7. The head 34 as well as the shank 27 20 has rounded corners or are rounded for a portion of their circumference, to facilitate free movement of the bolt actuating member thereon, as will be apparent upon inspection of Figures 4 and 5.

The head 34 is likewise provided with a narrow recess 35 disposed in registration with the recess 29 and pivotally mounted within the recess 35 is one end of a flat detent 36 that has its opposite end portion slidably mounted in the recess 29. The detent fittingly engages the walls of the recesses and couples the shanks together, so that they can be rocked by the knobs thereof for moving the bolt member against the action of its spring, through the medium of the actuating member, when the flat sides of the detent are disposed vertically, as shown in Figure 7. However, when the knob 28 is turned, from the position of Figure 7, about an angle of ninety degrees, the flat sides of the detent are horizontal, as shown in Figure 10, consequently the detent cannot move on its pivot and therefore the shanks cannot be rocked for moving the bolt member that normally has its head mounted within the keeper opening of the strike plate, 45 with the result the door is locked and cannot be opened until the detent is returned to the position of Figure 7, for allowing rocking movement of the shanks.

While the sleeve of the shank 30 is pivotally mounted for rocking movement in a vertical plane only, due to the fact that the pivot is fixed, the spindle is partially rotatably mounted within the sleeve and for that purpose the spindle is provided with diametrically disposed slots 37 for receiving the pivot pin 32, to allow for the turning movement of the knob 28, and it will be obvious from Figure 8, that the ends of the slots 37 provide stops to limit the turning movement of the knob 28, within a ninety degree angle, so that the detent is disposed either in the position of Figure 7, with the knob 28 horizontally arranged, or in the position of Figure 10, with the knob 28 vertically arranged.

The key actuated means in the form as shown, includes a cylinder lock 39 of the spring pressed tumbler type. The cylinder is mounted for rotation in the knob 31 and is connected to the spindle by any well known means, such as for example, a pin and slot connection 41, for movement 70 of the spindle 33 independently of the cylinder to allow the detent to be disposed to either of its positions, as shown in Figures 7 and 10, by the knob 28, regardless of whether or not the cylinder is in its locked or unlocked positions, and the 75

detent can be disposed to its respective positions upon rotation of the cylinder through the medium of the key 40.

It is believed that it will be obvious that the lock can be readily constructed without the key actuated means, for use with inside doors, particularly bathroom doors, and in that event the knob 31 would be solid like the knob 28 and the spindle would have its inner end terminating within the sleeve. A lock so constructed could be used on an inside door for locking and unlocking the same from one side only, that is by the knob 28.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A door lock comprising a casing, latching means within and movable through the casing and normally held in latched position, knobs provided with shanks pivotally mounted for rocking movement and extending into the casing, said shanks being connected to the latching means for operating the latter to unlatched position upon rocking movement of either knob, and means coupling the shanks to each other and movable by one of said knobs to a position to allow said rocking movement and to another position to prevent said movement.

35 2. A door lock comprising a casing, latching means within and movable through the casing and normally held in latched position, knobs provided with shanks pivotally mounted for rocking movement and extending into the casing, said shanks being connected to the latching means for operating the latter to unlatched position upon rocking movement of either knob, means coupling the shanks to each other and movable by one of said knobs to a position to allow said rocking movement and to another position to prevent said movement, and key actuated means carried by the other knob for moving the coupling means to either of its positions.

3. A door lock comprising a casing, latching means within and movable through the casing and normally held in latched position, knobs provided with shanks pivotally mounted for rocking movement and extending into the casing, said shanks being connected to the latching means for operating the latter to unlatched position upon rocking movement of either knob, rotatably mounted escutcheon means having the pivot of one shank carried thereby to allow rotation of the latter shank by its knob, rotatably mounted headed means included in the other shank, and detent means coupling the headed means to the rotatably mounted shank and movable to one position by the knob of the latter shank to allow said rocking movement and to another position to prevent said movement.

4. A door lock comprising a casing, latching means within and movable through the casing and normally held in latched position, knobs provided with shanks pivotally mounted for rocking movement and extending into the casing, said

shanks being connected to the latching means for operating the latter to unlatched position upon rocking movement of either knob, rotatably mounted escutcheon means having the pivot of one shank carried thereby to allow rotation of the latter shank by its knob, rotatably mounted headed means included in the other shank, means for limiting the rotation of the headed means, detent means coupling the headed means to the rotatably mounted shank and movable to one position by the knob of the latter shank to allow said rocking movement and to another position to prevent said movement, and key actuated means mounted in the other knob and connected to said headed means for moving the coupling means to either of its positions.

5. A door lock comprising a casing, latching means within and movable through the casing and normally held in latched position, knobs provided with shanks pivotally mounted for rocking movement and extending into the casing, said shanks being connected to the latching means for operating the latter to unlatched position upon rocking movement of either knob, rotatably mounted escutcheon means having the pivot of one shank carried thereby to allow rotation of the latter shank by its knob, a sleeve included in the other shank with the pivot thereof extending through the sleeve, a spindle rotatably mounted in the sleeve and having diametrically disposed slots therein with the latter pivot mounted in the slots to allow limited rotation of the spindle, a head on the spindle and having a recess therein, the rotatably mounted shank having a recess in the inner end thereof, a detent pivoted in one recess and slidably mounted in the other recess for coupling the spindle to the rotatably mounted shank, and said detent fitting the recesses and movable to one position by the knob of the latter shank to allow said rocking movement and to another position to prevent said movement.

6. A door lock comprising a casing, latching means within and movable through the casing, and normally held in latched position, knobs provided with shanks pivotally mounted for rocking movement and extending into the casing, said shanks being connected to the latching means for operating the latter to unlatched position upon rocking movement of either knob, rotatably mounted escutcheon means having the pivot of one shank carried thereby to allow rotation of the latter shank by its knob, a sleeve included in the other shank with the pivot thereof extending through the sleeve, a spindle rotatably mounted in the sleeve and having slots therein with the latter pivot mounted in the slots to allow limited rotation of the spindle, a head on the spindle and having a recess therein, the rotatably mounted shank having a recess in the inner end thereof, a detent pivoted in one recess and slidably mounted in the other recess for coupling the spindle to the rotatably mounted shank, said detent fitting the recesses and movable to one position by the knob of the latter shank to allow said rocking movement and to another position to prevent said movement, and key actuated means mounted in the other knob and connected to the spindle for moving said detent to either of its positions.
